SURGICAL DRAINAGE APPLIANCE

James M. Jones, Jr., 37 Ayrshire Road, Worcester, Mass.
 Continuation of application Ser. No. 717,254, Feb. 24,
 1958. This application June 13, 1960, Ser. No. 35,763
 4 Claims. (Cl. 128—275)

This is a continuation of my copending application Serial No. 717,254 filed February 24, 1958, and now abandoned.

This invention relates to surgical drainage appliances usable for instance to connect a catheter to a liquid collecting receptacle.

Following certain types of operation, it is usual hospital practice to insert a catheter in the patient and connect it by a drainage tube to some form of liquid collector or receptacle. Devices of this kind now in use have the common defect of not establishing a satisfactory connection between the tube and the receptacle, and as a result the tube is frequently pulled out of position due to movement of the patient.

It is an important object of the present invention to provide a connection between the tube and receptacle so constructed as to lock the tube to the receptacle to prevent their separation and at the same time establish a leak-proof connection which will remain water tight even though the receptacle should be tipped over.

It is common experience in hospitals that nurses have difficulty in connecting the catheter to the drainage tube in a manner which will secure the catheter and tube together tightly to prevent their separation. It is a further object of the invention to provide a simple form of resilient lock which can be readily moved into holding position after the catheter has been slipped over a connector or fitting on one end of the tube. In one form of the invention this form of resilient lock can also be used to connect the lower end of the tube to a fitting on either a rigid or bag type receptacle.

In the accompanying drawings which by example show four forms of the invention,

FIG. 1 shows a vertical section through the preferred form of the invention prior to complete assembly,

FIG. 2 is an enlargement of the upper end of FIG. 1,

FIG. 3 is an enlarged horizontal section on line 3—3, FIG. 1,

FIG. 4 is an enlarged vertical section of the lower part of FIG. 1 after complete assembly,

FIG. 5 is a view showing the preferred form completely assembled ready for use,

FIG. 6 is a vertical section similar to FIG. 4 showing the first modification, and

FIG. 7 is a view similar to a part of FIG. 4 showing the second modification.

Referring more particularly to FIGS. 1 to 5, the catheter C, which may be of the well known Foley type, has a lower end 1 which is elastic and can be readily stretched. The tube T preferably made of a plastic material such as polyethylene or polystyrene has a connector 2 at its upper end and has an attaching member 3 at its lower end for locking engagement with a fitting member 4 which has a tight fit with the neck 5 of a liquid receiver or receptacle R which may be a glass bottle. When these parts are assembled as shown in FIG. 5 they are ready for use, the catheter (upper end not shown) being inserted into the patient and attached to the connector 2 and the bottle resting on the floor.

The connector 2 is of double frusto-conical form having an upper part 10 which flares downwardly and a lower part 11 which tapers downwardly. The connector has a peripheral groove 12 extending around between the parts 10 and 11. A resilient ring 13, such as an elastic rubber band or open metal spring ring, has a normal

2

internal diameter less than the largest diameter of the connector and can be nested in groove 12 to prevent loss, or be held frictionally by slight expansion around part 11, or surround the tube.

When the catheter is to be fitted to the connector the ring 13 will be in some such position as shown in dotted lines in FIG. 2 and the lower end of the catheter will be stretched over the upper conical part 10 and also over part at least of the lower part 11 so that it extends over the groove 12. The ring is then pushed up along part 11 over the bottom end of the catheter until it reaches the groove, whereupon it will snap into the groove due to its resilience and will thus hold the catheter firmly in position on the connector 2. The latter has a passage 15 which communicates with the passage 16 in the catheter and also the passage 17 in tube T.

The neck 5 of the bottle R has a top lip or rib 20 and a lower rib 21 the top and bottom sides of which are inclined as shown in FIG. 4. The fitting member 4 has a top 22 and a cylindrical shell 23 depending therefrom. An internal circular rib 24 fits snugly under lip 20 and cooperates with the top 22 to hold the upper part of the shell to the lip 20 and top of the bottle neck. A second lower internal circular rib 25 on the shell fits snugly under the rib 21 and is shaped to fit closely against the under side of rib 21. A tab 26 extends from a side of the shell, all as shown in FIG. 4. The top 22 is formed with a downwardly inclined funnel shaped locking part 27. Vent holes 28 are provided in the top 22.

The attaching member 3 secured to the lower end of tube T is formed at its lower end with a laterally projecting shoulder 30 extending around the member 3. The outside diameter of this shoulder is somewhat greater than the normal inside diameter of the ring 13 to prevent loss of the ring from the bottom of the tube. The normal inside diameter of the opening 31 at the bottom of the funnel shaped part 27 is preferably slightly less than the outside diameter of the cylindrical shank 32 of the attaching member 3. The shoulder 30 may flare upwardly at about the angle of the funnel part 27, but this is not essential. The passage 33 in the member 3 communicates with passage 17 and the interior of the bottle.

With the several parts in the positions shown in FIG. 1, the left-hand part of fitting member 4 will be moved down along the left side of neck 5 and then be stretched by tab 26 until the member is in the position shown in FIG. 4 and is firmly attached to the neck of the bottle. The part 3 is then forced down into the funnel, part 27, spreading the latter sufficiently to allow the shoulder 30 to pass, after which the funnel part will snap back over the shoulder and against the shank 32 thus interlocking the parts 3 and 4 and creating a leak-proof seal of the part 27 around the shank 32. The fitting member 4 is made of a material, such as polyethylene, which is sufficiently resilient and elastic to permit the operations described.

In the form of the invention already set forth the parts connecting the catheter to the receptacle are preferably made of plastic material such as polyethylene or polystyrene. The tube T is cemented or otherwise suitably secured to the connector 2 and attaching member 3 and although it is flexible it is not very elastic. In the first modification shown in FIG. 6 the invention is shown as being adaptable to use with an elastic tube T'.

In FIG. 6 the fitting member 40 has its lower part similar to the corresponding part of member 4, but its top 41, instead of being funnel shaped, extends across the shell 42 and has formed integral with it an upwardly tapering connector 43 formed with a peripheral groove 44 similar to groove 12. The tube T' is soft elastic rubber and can be easily stretched over connector 43 after which a ring 45 is slipped down to

the position shown in FIG. 6 to squeeze the adjacent part of tube T' into the groove 44 in a manner similar to that already described for the form shown in FIG. 2. A passage 46 through the connector 43 connects the passage 47 in tube T' with the interior of the receptacle (not shown but similar to bottle R) to which the member 40 is fitted. The upper end of tube T' can be connected to the catheter as for instance by a part similar to connector 2, or in any other convenient manner.

In certain uses to which the invention can be put, offensive odors arise from the contents of the receptacle and it is a further object of the invention to provide means to counteract or suppress these odors. FIG. 7 shows such a means applied for instance to the lower end of the drainage tube such as shown in the preferred form. A collar 80 of porous preferably textile material, such as felt, surrounds the fittings at the lower end of tube T and has a conical part 81 which fits into the funnel like top of part 4 and has a flange 82 overhanging the vents 28 but spaced above the top of part 4 to permit escape of air as the receptacle fills up. A deodorant preferably in liquid form is dropped on the collar, saturating the latter and being held by the flange in the path of air arising from the vents to check objectionable odors. The collar has a bore 84 which snugly fits the part 4 and tube T and is too small to pass the fittings at the upper and lower ends of the tube. The collar is thus held against loss and is disposable with the tube and the parts connected to it.

From the foregoing, it will be seen that I have provided a surgical drainage appliance including a connector with a groove to receive a lock or holding ring either for a catheter or for a fitting for a receptacle. The ring because of its size cannot become accidentally disconnected from the tube, being confined between the fittings at the ends of the tube. In the first modification a rubber tube can be used and in the second modification an absorbent collar covers the vent holes and can be treated with a deodorant. In the first form the lower end of the tube can be pushed down into the receptacle to permit ready inspection of the drippings from the tube and then pulled up to the normal position shown.

I claim:

1. In a surgical drainage appliance, a liquid receiver formed with a neck, a fitting member surrounding the neck and having a vent hole in the top thereof, a tubular drain means passing down through the fitting member into the receiver, a collar of absorbent deodorant holding material surrounding the tubular means, and means centering the collar with respect to the tubular means and effective to hold the collar spaced above said fitting member and vent hole.
2. The appliance set forth in claim 1 wherein the tubular drain means has a catheter connector on the upper end thereof and an attaching member on the lower end thereof interlocked with the fitting member and said collar is prevented from slipping off the drain means by said connector and said attaching member.
3. The appliance set forth in claim 1 wherein the fitting member has a downwardly directed funnel part between the vent and the tubular drain means and the absorbent material fits into said funnel part and the latter limits down motion of said absorbent material.
4. The appliance set forth in claim 3 wherein the absorbent material is formed with a flange extending over the vent and held spaced above the vent by engagement of the absorbent material with said funnel part.
